STOP WATCH CASING

Gerald Ray Doss, 14655 Colt Road,
Dallas, Tex. 75240

Filed Aug. 26, 1974, Ser. No. 500,974

Term of patent 14 years

Int. Cl. D10—02

U.S. CL. D10—40

Fig. 2

Fig. 1

Fig. 5

Fig. 6

FIG. 1 is a top, front, and right side perspective view of a stop watch casing showing my new design with display activated;

FIG. 2 is a front end elevational view thereof;

FIG. 3 is a top, rear, and left side perspective view thereof;

FIG. 4 is a bottom plan view thereof;

FIG. 5 is a top plan view thereof with display activated; and

FIG. 6 is a left side elevational view thereof.

I claim:

The ornamental design for a stop watch casing, substantially as shown and described.
